DESK TRAY

Carl W. Jarvi, Wexford, Pa., assignor to Haskell Manufacturing Company, Inc., Pittsburgh, Pa., a corporation of Pennsylvania

Application November 13, 1956, Serial No. 43,742

Term of patent 14 years

(Cl. D74—1)

Fig. 1 is a top perspective view of a desk tray showing my new design, and

Fig. 2 is an end elevational view thereof.

The back of the tray is plain and unornamented, and the end opposite to that shown in Fig. 2 presents a similar appearance.

I claim:

The ornamental design for a desk tray, as shown and described.
